UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

CONFECTION-COATING MACHINE.

Application filed October 31, 1922. Serial No. 598,220.

To all whom it may concern:

Be it known that I, ALONZO LINTON BAUSMAN, citizen of the United States, residing at Springfield, in the county of Hampden and State of Massachusetts, have invented new and useful Improvements in Confection-Coating Machines, of which the following is a specification.

This invention relates to improvements in 10 confectionery coating machines and is particularly concerned with the provision of improved means tending to prevent the formation of the disfiguring "tails" commonly formed on the coated confections during 15 their transfer from one conveyer to another.

Examples of prior machines having this object in view will be found in U. S. Letters Patent No. 1,302,205, granted April 29, 20 1919 on an invention of Antonio Pagliuca and in U. S. Letters Patent No. 1,341,253 granted May 25, 1920 to Alonzo Linton Bausman. These machines, as well as all others of which I am aware, attain their 25 object by means which are located between the two conveyers and which eliminate the tail after its formation. They also require the addition of the tail removing mechanism as an adjunct to the machine and require a 30 relatively large gap between the conveyers to receive the tail removing part of such mechanism.

According to this invention, the desired result is accomplished by properly shaping 35 that roll, which underlies the upper lap of the previous coating machine conveyer at its delivery end, so that those portions of the conveyer supporting the confections are enabled to contact with the surface of this 40 roll,—this result being hitherto prevented by connecting portions underlying the first named portions and holding the latter out of contact with the roll.

With the described arrangement those 45 portions of the coatings, which drip from the confection and depend through the previous conveyer, are wiped off by the specially formed roll leaving nothing to be subsequently drawn out during the transfer 50 to the delivery conveyer to form a tail. In other words, the improvement tends to prevent the formation of a tail while the prior machines permitted the formation of a tail and later removed it.

According to a further feature of the invention the described roll is preferably driven at a surface speed greater than that of the previous conveyer.

Other features and advantages will appear in the following description and in the 60 illustrative embodiment of the invention in the accompanying drawings, in which:

Fig. 1 is a plan view, with parts broken away, showing the delivery end of the previous conveyer of a confectionery coating 65 machine, embodying the invention;

Fig. 2 is a sectional elevational view thereof;

Fig. 3 is an enlarged fragmentary view taken similar to Fig. 2 and illustrating the 70 operation of the invention;

Figs. 4 and 5 are small scale front and rear elevational views, respectively, of the coating machine, illustrative of the driving connections for the parts shown in Figs. 1 75 and 2; and

Fig. 6 is a fragmentary cross-sectional view showing the invention applied to a different type of previous belt.

Referring to these drawings: A represents the casing of a confectionery coating machine, which may be of any suitable type and a full disclosure of one suitable type will be found in U. S. Letters Patent No. 790,184, granted May 16, 1905, on an invention of Gabriel Carlson. The particular details of the coating machine may be varied, as desired, and the present invention is concerned only with the fact that the confections, coated in any desired way, are 90 carried on a previous conveyer, such as 10, at a time when their coatings are still soft and workable and transferred to another conveyer, such as 11, which may be and is usually the delivery conveyer,—a non-pervious belt by which the coated confections are carried away to the cooling room.

The conveyer 10 may be variously constructed, as desired, but usually is in the nature of a wire screen, or interlaced wire fabric, which permits of excess coating dripping from the confections during their travel. One common way of constructing conveyer 10 is clearly illustrated in Figs. 1 and 2 in which a plurality of wires, each 105 bent to provide alternate offset parallel portions 12 and 13 connected by portions 14, are interlaced to form an endless pervious

conveyer or wire belt. The portions 12 and 13, or transverse members of the conveyer, all lie in one common horizontal plane and afford a smooth, flat, confection-
 5 supporting surface. The portions 14, forming the longitudinal members of the conveyer, do not project above the plane of the portions 12 and 13 and are largely located therebelow as will be clear from Figs.
 10 2 and 3. At least there are portions of the members 14 which extend below the trans-
 15 verse members 12 and 13 by distances equal to the diameter of the wire of which these members are formed and in all prior coating machines (utilizing so called wire belts) the portions 14, or equivalent portions, contact with the periphery of the supporting rolls for the wire belt and hold the portions 12 and 13, or confection supporting
 20 members, out of contact with the rolls.
 The action, just described, is not partic-
 25 ularly material except at the delivery end of the coating belt but, at this location, drippings from the confections clinging to the wire belt are drawn out during their transfer to belt 11 to form disfiguring tails, as outlined in the above named Pagliuca patent. I have found that the formation of these tails may be practically eliminated
 30 if the conveyer supporting roll, used at the described location, is properly formed. Thus, instead of the ordinary plain and ungrooved roll heretofore used with previous conveyers of the type described, I em-
 35 ploy a roll 15, which is grooved, as at 16, at suitable axially spaced intervals to receive the longitudinally disposed and underlying portions 14 of the conveyer 10. These grooves are of such depth as to allow the
 40 transverse members 12 and 13 to lie flush and contact with the periphery of roll 15 and this allows the roll to come into very close proximity to the bottom of a confection, such as *c*, and exert a wiping action
 45 to either remove the tails or rework them under the bottoms of the confections. In fact, the top surface of roll 15 will contact with the bottom of the confection when the conveyer is positioned, as in Fig. 3, and
 50 the dripping *d* will be gradually wiped off, or worked into the bottom of the confection, being entirely eliminated as the rear end of the confection moves out of contact with roll 15.
 55 The conveyer 10 used in chocolate coating machines, is sometimes made like that disclosed in U. S. Letters Patent No. 1,009,-
 670, granted Nov. 21, 1911 on an invention of Theodor and David Kihlgren. Such a
 60 conveyer is made up of members interlaced in the same general fashion, as heretofore set forth, except that the transverse members are of substantially zigzag shape (Fig.
 65 6) and have inclined portions 17 and shoulders 18. The roll, as 15' used with this

type of conveyer has grooves 16, as before, to receive the portions 14 and is turned up to provide frusto-conical portions 19 and 20 to accommodate the portions 17 and 18 of the conveyer supporting members and the 70 tail removing action is effected, in a similar manner to that already described, by the frusto conical portions 19.

The conveyers 10 and 11 may be sup-
 75 ported and driven in any suitable manner and, as an illustrative example, the arrangement shown in Figs. 4 and 5 may be used for driving the parts from the coating machine, of which 21 is the main driving shaft. Shaft 21 drives a shaft 22 by means of a belt 23 and cone pulleys 24 and 25, the latter forming the usual speed changing de-
 80 vice. Shaft 22 drives by bevel gears 26 a vertical shaft 27 which in turn drives through bevel gearing 28 a horizontal shaft 29. The latter carries a gear 30, which through the intermediary of a train of gears conventionally represented at 31, drives a gear 32 on a shaft 33 which extends across the machine beneath belt 10 and carries on its opposite end (Fig. 5) a gear 34. Gear 34, through a gear train 35 drives a shaft 36, which carries a roll 37, constituting the driving roll for conveyer 10. Referring now to Fig. 4, the gear 32 heretofore de-
 85 scribed, meshes with an idler gear 38, which drives a pinion 39, fixed on the end of a roll 15. Referring now to Fig. 5, the main drive shaft 16 is connected to spur gears 40 to drive a parallel shaft 41, which by means of a belt 42 (Fig. 4) and cone pulleys 43 and 44 drives a shaft 45. The latter, as shown in Fig. 5, drives through bevel gearing 46 a vertical shaft 47, which in turn drives through bevel gearing 48 a short shaft 49. The latter is connected by spur 90 gearing 50 to a shaft 51 which through a worm 52 and worm gear 53 drives a shaft 54 carrying a roll 55, which is the driving roll for conveyer 11. The latter is supported by suitable means (not shown) in the usual known manner.

Preferably, a scraper 56 (Fig. 2) is as-
 95 sociated with roll 15, or 15', the scraper be-
 100 ing cut to conform to the contour of these rolls. This scraper is mounted in the cus-
 105 tomary manner, being held in an arm 57 which is mounted on a bushing 58 concent-
 110 trically arranged with respect to the axis of roll 15.

Preferably, the roll 15 is driven at a sur-
 115 face speed greater than that at which con-
 120 veyor 10 is driven. As a convenient practi-
 125 cal way of obtaining this result without any change in the standard driving mechanism of the coating machine, the roll 15 is made larger in diameter than the standard roll which it replaces, such standard roll being ordinarily driven by the gearing described at the same surface speed as conveyer 10.

By using the same gearing and merely removing the pinion 39 from the standard roll and replacing it on the roll 15, the desired result is obtained,—the only change in the 5 coating machine being the provision of the roll 15.

Aside from making the roll 15 perform the double function of a conveyer supporting roll as well as the wiping function 10 herein described, I conceive that there is a cooperation between the cross members 12 and 13 and the roll 14 in pinching off the drippings *d*. That is the wires 12 and 13, which move at a slower speed than the periphery of roll 15, furnish edges against 15 which the drippings of the coating are carried by roll 15 and pinched off in a manner closely analogous to a scissors, or shearing action, which I believe materially improves 20 the results accomplished.

The invention has been disclosed herein, in an embodiment at present preferred, for 25 illustrative purposes but the scope of the invention is defined by the appended claims rather than by the foregoing description.

I claim:

1. In a confection coating machine, of the type wherein the coated confections are transferred from the upper lap of a previous conveyer to another conveyer while 30 their coatings are still workable, driving means for said conveyers, a roll underlying the upper lap of the previous conveyer at its delivery end, and means for driving said 35 roll at a surface speed greater than that of said previous conveyer.

2. In a confection coating machine, a previous conveyer adapted in its upper lap of travel to carry the confections while their 40 coatings are still workable, said conveyer comprising a fabric having spaced confection supporting portions and other underlying and connecting portions, and a roll supporting the conveyer in its upper lap of 45 travel at the delivery end thereof, said roll being grooved to receive said underlying portions and allow the other portions to contact with the surface of said roll.

3. In a confection coating machine, a previous conveyer adapted in its upper lap of travel to carry the confections while their 50 coatings are still workable, said conveyer comprising a fabric having generally transverse portions to support the confections and underlying and generally longitudinal 55 connecting portions, and a roll underlying the conveyer in its upper lap of travel and disposed at the delivery end thereof, said roll being grooved to receive said longitudinal portions and allow said transverse portions to 60 contact with the surface of said roll.

4. In a confection coating machine, a previous conveyer adapted in its upper lap of 65 travel to carry the confections while their

coatings are still workable, said conveyer comprising a fabric having spaced confection supporting portions and other underlying and connecting portions, a roll supporting the conveyer in its upper lap of travel 70 at the delivery end thereof, said roll being grooved to receive said underlying portions and allow the other portions to contact with the surface of said roll, and means to drive said roll at a surface speed greater than that 75 of said conveyer.

5. In a confection coating machine, a previous conveyer adapted in its upper lap of travel to carry the confections while their 80 coatings are still workable, said conveyer comprising a fabric having generally transverse portions to support the confections and underlying and generally longitudinal connecting portions, and a roll underlying the conveyer in its upper lap of travel and disposed at the delivery end thereof, said 85 roll being grooved to receive said longitudinal portions and allow said transverse portions to contact with the surface of said roll, and means to drive said roll at a surface speed greater than that of said conveyer.

6. In a confection coating machine, a previous conveyer adapted in its upper lap of 90 travel to carry the confections while their coatings are still workable, said conveyer comprising a fabric having generally transverse portions of substantially zigzag shape and underlying and generally longitudinal 95 connecting portions, and a roll underlying the conveyer in its upper lap of travel and disposed at the delivery end thereof, said roll being grooved to receive said longitudinal portions and otherwise so shaped that said transverse portions contact with 100 the surface of the roll.

7. In a confection coating machine, a previous conveyer adapted in its upper lap of travel to carry the confections while their 105 coatings are still workable, said conveyer comprising a fabric having generally transverse portions to support the confections and underlying and generally longitudinal connecting portions, a roll underlying the conveyer in its upper lap of travel and disposed at the delivery end thereof, said roll being grooved to receive said longitudinal portions and allow said transverse portions to 110 contact with the surface of said roll, and scraping means engageable with said roll.

8. In a confection coating machine, a previous conveyer adapted in its upper lap of travel to carry the confections while their 115 coatings are still workable, said conveyer comprising a fabric having generally transverse portions of substantially zigzag shape and underlying and generally longitudinal connecting portions, a roll underlying the conveyer in its upper lap of travel and disposed at the delivery end thereof, said roll 120

being grooved to receive said longitudinal portions and otherwise so shaped that said transverse portions contact with the surface of the roll, and scraping means engageable 5 with said roll and shaped to conform to the contour thereof.

9. In a confection coating machine, of the type wherein the coated confections are delivered from the upper lap of a wire mesh 10 conveyer to another conveyer while their coatings are still soft, a roll underlying the upper lap of the first named conveyer at its

delivery end and shaped to allow the confection supporting portions of the conveyer to contact with the periphery of the roll, whereby those portions of the coatings depending from the confections through the first conveyer may be engaged by and wiped off by said roll, and means for driving said roll at a surface speed greater than that of 15 said wire mesh conveyer.

In testimony whereof I have affixed my signature.

ALONZO LINTON BAUSMAN.
